CARTON

William A. Ringler, Wayne, Pa., assignor to National Folding Box Company, New Haven, Conn., a corporation of New Jersey

Application June 24, 1936, Serial No. 86,917

13 Claims. (Cl. 229—6)

This invention relates to cartons, and more particularly to a carton for the packaging of radio tubes, electric light bulbs and similar articles, which require testing to determine whether they are in good, serviceable condition before delivery to the customer.

Customers generally require an actual test of such articles as radio tubes and electric light bulbs to determine whether they are in serviceable condition before accepting delivery of same. Such test requires that the test end of the article be inserted in a suitable electric socket to determine whether the article properly responds to the current or energy waves to which it is subjected. Irresponsible dealers and bootleggers have heretofore taken advantage of this requirement by actually removing the article originally packed by the manufacturer in the carton, and inserting a used or inferior article in its place. Legitimate manufacturers naturally desire to safeguard their product and their customers against such operations, and to this end this invention is directed.

An object of this invention is to provide a carton especially adapted for the packaging of radio tubes, electric light bulbs, and similar articles, which permits full and complete test of the article before use, but which is so constructed as to prevent unauthorized removal of the original article from the carton.

Another object of this invention is to provide an improved carton for articles to be tested prior to use, which permits a limited movement of the article within the carton for purpose of test, but which will effectively prevent unauthorized removal of the article therefrom, thus insuring delivery of the original article to the customer.

Still another object of this invention is to provide an improved carton for articles to be tested prior to sale, which fully protects the article from injury resulting from external shock, which permits quick manipulation of the article for purpose of test and yet positively prevents unauthorized removal of the article therefrom, which carton can be inexpensively and economically manufactured, assembled and packed substantially entirely by automatic machinery, and which is susceptible of being formed into a variety of attractive designs and patterns.

Other objects of this invention will become apparent as the disclosure proceeds.

Although the novel features which are believed to be characteristic of this invention will be particularly pointed out in the claims appended hereto, the invention itself, as to its objects and advantages, and the manner in which

it may be carried out, may be better understood by referring to the following description taken in connection with the accompanying drawings forming a part thereof, in which:

Fig. 1 shows an extended blank from which the outer tubular member of the carton may be formed;

Fig. 2 shows an extended blank from which the sliding inner sleeve of the carton may be formed;

Fig. 3 is a perspective view of the inner sleeve as it appears when assembled;

Fig. 4 is a perspective view of the inner sleeve containing a tube-protecting shell about to be enclosed within the outer tubular member;

Fig. 5 shows the assembled carton having a radio tube packed therein, the test end of which has been ejected into test position, certain parts being broken away to illustrate certain features of the construction;

Fig. 6 shows a blank from which the outer tubular member of a carton of somewhat modified form may be made;

Fig. 7 is a blank from which the inner tubular sleeve telescoping within the outer tubular member formed from the blank shown in Fig. 6, may be made;

Fig. 8 is a perspective view of the outer tubular member and the inner sleeve assembled from the blanks shown in Figs. 6 and 7 respectively, as they appear when partly assembled;

Fig. 9 is a perspective view of the carton as it appears fully assembled from the blank shown in Figs. 6 and 7, this view showing the test end of a radio tube ejected for purpose of test, certain parts being broken away to illustrate the internal construction thereof; and

Fig. 10 is a perspective view of a carton formed from the blank shown in Figs. 6 and 7, said blanks being assembled together in a somewhat different manner than that shown in Fig. 8.

Similar reference characters refer to similar parts throughout the several views of the drawings and specification.

The carton forming the subject-matter of this invention is particularly designed for the packaging of radio tubes, electric light bulbs, and similar articles requiring test before use, which articles will be hereinafter designated T. The carton comprises generally an outer tubular member A which contains an inner sliding member B. The inner sliding member supports the article T which may be encased in a protective shell C. Means are provided to permit limited sliding movement of the inner sliding member within the outer tubular member so that the ar-

ticle-can be tested when desired. The carton is so constructed, however, that the article cannot be removed without mutilating or destroying the carton or otherwise leaving visible evidence that the carton has been tampered with and access to the article originally packed therein obtained.

Referring more particularly to Figs. 1 to 5 inclusive, the outer tubular member A may be formed from the blank shown in Fig. 1, comprising side wall-forming sections 1, 2, 3 and 4, defined by the longitudinally extending score lines 6. A closure section 5 hinged to the side wall section 2 along the score line 6 is arranged to overlap the side wall section 1 to form a closed tubular outer member. The manner in which the outer tubular member is closed and sealed will be discussed more in detail hereinafter.

Fig. 2 shows a blank from which the inner 20 slideable member B may be formed, comprising a bottom wall section 11 and a top wall section 12 connected to the side wall section 10 along the score lines 18. The bottom section 11 is provided with an opening 19 through which the test end p of the article T may project. The top wall section 12 is provided with a suitably shaped opening 20 through which an instrument, such as a finger, may be inserted to slidably telescope the article within the outer tubular member. Side 25 wall portions 13 and 16, hinged respectively to the bottom wall section 11 and the top wall section 12 along the score lines 18, are provided with hook portions 21 which may be interlocked together when the article has been placed therein.

In packaging the carton, the article T is first telescoped into the corrugated shell C comprising the surrounding side walls 30. The shell C serves as a cushion to protect the fragile article against injury from shock. The inner member or sleeve 35 B is then wrapped around the article T and the protective shell C by first placing the test end of the article in supporting position on the bottom section 11, with test prongs p projecting through the opening 19. The top wall section 12 is then placed over the top end of the article, the opening 20 serving to center the article in position. The side wall-forming portions 13 and 16 are then 40 swung into position and connected by means of hook portions 21 so that the side wall portions 13 and 16 form a fully assembled side wall section 45 positioned opposite to the side wall section 10.

The article T, corrugated protective shell C, and inner sleeve B, assembled as above described, is then ready to receive the outer tubular member. In performing this final assembly operation, the leg portions 15 and 17 of the inner sleeve are bent outwardly and the side wall sections 1, 2, 3 and 4 of the outer member are wrapped around the sleeve as shown in Fig. 4. The side wall section 1 of the outer member is provided with a pair of slits 28 which extend from the free edge of the section 1 inwardly a substantial distance so as to define a tab or ear 25. The tab or ear 25 is inserted through an elongated slit 26 cut through the side wall section 10 of the inner sliding member, so as to lie between the inside face of the side wall section 10 and the adjacent outside face of the wall 30 of the protective shell C, as fully shown in Figs. 4 and 5. The section 5 of the outer member is then positioned over the side wall section 1, and is secured in position at each end thereof by the eyelets 27 which may be inserted through the aligned openings 27 in the sections 1 and 5. When thus arranged it will be noted that the inner sliding

member B has a limited sliding movement within the outer tubular member A which is defined by the length of the slot 24 and the width of the tab 25. Thus, when the article T is fully housed and contained within the outer member during 5 shipment and storage, the edge portion 26a of the tab 25 will abut against the lower edge 24a of the slot 24. When the test portions p of the article T is ejected into test position, as shown in Fig. 5, the edge portion 26b will abut against the upper end 24b of the slot 24, shown in Fig. 5. The width of the tab 25 and the length of the slot 24 is such as to permit the desired limited telescoping movement of the inner member B within the outer member A. The article T and inner 15 member B are supported by the leg portions 15 or 17, as the case may be, when the corresponding end of the carton rests on a supporting surface, such as a shelf. Thus the article T is held out of contact with such supporting surface. 20

It will be noted that when the carton is assembled the tab 25 is completely concealed from view and is so arranged as to make it impossible to withdraw the tab 25 from its locked position without visibly mutilating the carton. The eyelets 29 are provided with edge portions 29a which overlap and press into the paperboard material, making it impossible to remove or loosen the eyelets 29 without mutilating the eyelets and the surrounding paper board material. The overlapping section 5 is thus permanently secured to the side wall section 1 to form a permanent tubular outer member which cannot be opened or released without visibly mutilating the material from which it is made. When the outer tubular member is sealed, it is impossible to insert any instrument in any manner into or between the side walls of the carton to release the tab 25 from its locked inserted position. 35

There is shown in Fig. 6 a blank from which 40 a somewhat modified form of outer tubular member A may be formed, which outer tubular member is adapted to receive an inner sliding member B formed from the blank shown in Fig. 7. The blank shown in Fig. 7 is assembled around the 45 article T encased within the inner protective shell C by first inserting the test end of the article through the opening 19 in the bottom wall section 11. The top wall section 12 is arranged to overlie the opposite end of the article, with 50 the opening 20 therein serving to center the article within the inner member. The side wall portions 13 and 16 are then connected together by means of the hook portions 21 to enclose the article T and the inner protective shell C. When 55 thus assembled, the side wall portions 13 and 16 together form a side wall section oppositely arranged with respect to the side wall section 10.

The outer tubular member is provided with a flap portion 41 hinged at 43 to the side wall section 2 and a flap portion 42 hinged at 43 to the side wall section 4. The outer member is also provided with a securing flap 48 which may be hinged to the side wall sections 1 or 4 along the score line 6. 60

In assembling the outer member around the assembled article-containing inner member, the flaps 41 and 42 are turned inwardly so as to overlie the inside face of the side wall sections with which they are associated, shown in Fig. 8. 70 The flaps 41 and 42 are each provided with tabs or ears 44 which are inserted into longitudinally extending slits or slots 51 associated with the side wall section 10 of the side wall portion 16 of the inner member respectively, which slits 75

may extend from adjacent the top wall section 12 downwardly a predetermined distance. Each tab or ear 44 is preferably inserted through the adjacent slot 51 so that a substantial portion thereof lies against the inside face of the adjacent side wall section 10 and the inside face of the side wall portion 16 respectively and the article-containing shell. The leg portions 15 and 17 are then turned outwardly and finally the securing flap section 40 is secured preferably to the inside face of the adjacent side wall section 4 as by the eyelets 29. The outer tubular member is thus permanently held in tubular assembly and cannot be opened without visibly mutilating the outer member. As thus assembled, it will also be noted that it is impossible to insert any instrument into or between the walls of the carton to retract the tabs or ears 44 without mutilating the structure. It will be further noted that the eyelets 29 are so arranged with respect to the leg portions 15 and 17 that the eyelets 29 can be quickly applied by automatic machinery without interference from the leg portions 15 and 17 or other parts of the construction. The sliding movement of the inner member is positively limited by the width of the tabs or ears 44 and the length of the slots. When the inner sliding member is in shipping or storage position, the lower edge portion 44a of the tabs seat against the lower ends 51a of the slots 51 respectively, as illustrated in Fig. 8. When the test end p of the article is ejected into test position, the edge portion 44b of the tabs 44 will seat against the opposite end 51b of the slots 51, thus definitely limiting the test position of the inner sliding member. The leg portions 15 when in test position are free to swing outwardly, as shown in Fig. 9, so as not to interfere with the free testing of the article.

While the outer tubular member may be made with only one flap and associated locking tab 44, it is generally desirable to provide two oppositely arranged flaps 41 and 42 with associated locking tabs 44, so as to insure smooth sliding movement of the inner member within the outer member. The friction exerted by the side walls of the outer member against the inner sliding member and associated protecting sleeve, as well as the friction exerted between the tabs 44 and the edges of the slots 51, is sufficient to hold and normally maintain the article T completely housed within the outer tubular member. A slight pressure on the inner sliding member or the article is only required to eject the same into test position and to retract the same into the outer tubular member.

Figs. 8 and 9 illustrate a carton assembly in which the slots 51 are arranged adjacent to the head and/or top wall section 12 of the carton. If desired, however, the slot 51 in the side wall sections of the inner sliding member may be positioned adjacent the ejecting end or bottom end section 11 of the carton, as shown in Fig. 10.

The cartons herein described provide highly satisfactory and serviceable packaging mediums for radio tubes, electric light bulbs, and like articles which must be protected against damage and injury during shipment and storage and from unauthorized pilfering of the original contents. The inner member slides within the outer tubular member smoothly and evenly with just sufficient friction to prevent the article from being ejected by jars in a test position, but requiring only a slight pressure on the article T or on the inner sliding member to effect ejec-

tion of the test portion p of the article for unobstructed testing. The leg portions 15 or 17 serve to support the inner sliding member in housed position within the outer member when the carton is placed on a supporting surface, such as a shelf. The leg portions at the lower end of the carton freely swing outwardly so as to be completely out of the way when the test of the article is being made. The leg portions at the other end of the sliding inner member support the head end of the article away from the surface on which the carton rests, should the carton be placed on the supporting surface in an upside down position. The cartons herein disclosed can be economically made with a minimum of paperboard material and can be assembled and packed automatically and substantially entirely without hand operation. The cartons are so constructed that the original articles packed therein cannot be removed therefrom without first mutilating or destroying the material from which the carton is made, so as to make visibly apparent that access to the contents has been made. The customer, when a legitimate manufacturer desires to protect, can be warned not to accept from any dealer a packaged article of which the carton bears evidence of mutilation. Thus, the manufacturer as well as the user is assured of obtaining the article originally packed in the carton in good and serviceable condition.

While certain novel features of the invention have been disclosed and are pointed out in the annexed claims, it will be understood that various omissions, substitutions and changes may be made by those skilled in the art without departing from the spirit of the invention.

What is claimed is:

1. A carton for a radio tube and the like including, an outer tubular member, an inner tube-supporting member telescoping within said outer member, said outer member and inner supporting member having a cooperating slit and tab means associated therewith permitting limited telescopic movement only of said inner member within the outer member, said cooperating means being so arranged as to be inaccessible from outside the container, said slit being of limited predetermined length and wholly surrounded by the material from which the member with which the slit is associated, is made.

2. A carton for radio tubes and the like including, an outer tubular member, and an inner tube-supporting member adapted to telescope within said outer member, said inner member having end wall portions and side wall portions connecting said end wall portions, said outer member and inner member having a cooperating slit and tab associated therewith permitting limited telescopic movement of said inner member within the outer member, said slit being of limited predetermined length and wholly surrounded by the material forming a part of the member with which said slit is associated, and an overlying side wall section associated with said outer member covering said slit and tab so that the same cannot be removed or detached to effectuate removal of the tube without leaving telltale evidence of tampering.

3. A carton for a radio tube and the like including, an outer tubular member, an inner tube-supporting member telescoping within said outer member, a guide slit of limited predetermined length cut in said inner member and wholly sur-

- rounded by the material from which said inner member is made, a guide tab projecting from said outer member and extending through said guide slit permitting limited telescopic movement of said inner member within the outer member, and means associated with said outer member covering and concealing said guide tab so as to prevent unauthorized access thereto.
4. A carton for radio tubes and the like including, an outer tubular member having side wall panels forming a container of generally rectangular form, and an inner tube-supporting member adapted to telescope within said outer member, said inner member having end wall sections and side wall sections connecting said end wall sections, said outer member having an integral tab portion extending inwardly from one end thereof adapted to interlockingly engage with a slit of predetermined length cut in said inner member to permit limited telescoping movement thereof within defined limits only, and means for sealing said outer member in fixed tubular position which cannot be detached without leaving visible evidence of tampering.
5. A container for radio tubes and the like including, an outer tubular member having side wall-forming sections, and an inner tube-supporting member adapted to telescope within said outer member, said outer member having an integral tab portion adapted to be inserted into an enclosed opening in said inner member so as to permit limited telescoping movement only of said inner member within the outer member, and means for permanently sealing said outer member in fixed tubular position.
6. A container for radio tubes and the like including, a tubular outer member, an inner member adapted to contain a tube telescoping within said outer member, a guide tab extending laterally from said outer member projecting through an elongated guide slot in said inner member so as to permit limited telescoping movement of said inner member within the outer member, said outer member having a side wall section adapted to overlie said guide tab so as to prevent unauthorized release of said guide tab from said guide slot without leaving visible evidence of tampering.
7. A container for radio tubes and the like including, a protective shell, an article-supporting member enclosing said protective shell, and an outer tubular member having side walls enclosing said article-supporting member, said article-supporting member including end wall sections and a side wall section connecting said end wall sections, said outer tubular member having a guide flap integrally formed with one of said side walls inserted between said inner protective shell and said side wall section, said guide flap extending into an enclosed opening of predetermined length limiting and defining the extent of sliding movement of said inner member in said outer tubular member.
8. A package for radio tubes and the like including, an inner protective shell enclosing the tube, an inner member surrounding said protective shell, and an outer member enclosing said inner member, said outer member having an integral guide flap inserted into an enclosed slit

cut in said inner member to limit and define the sliding movement thereof.

9. A package for radio tubes and the like including, an inner protective shell enclosing the tube, an inner member surrounding said protective shell, and an outer member enclosing said inner member, said outer member having an integral guide flap extending from one edge thereof having a portion inserted into a slit of predetermined length cut in said inner member to limit and define the sliding movement thereof.

10. A container for radio tubes and the like including, an outer member, an inner member adapted to contain a tube telescoping within said outer member, said inner member including end wall sections and side wall sections connecting said end wall sections, one of said end wall sections having an opening through which the test end of the tube may be projected for test purposes, and a projecting portion integrally formed on one of said members cooperating with a slit opening provided on the other member to define and limit the telescoping movement of the test end of the tube, said slit opening being of limited predetermined length and being wholly surrounded by the material of said member with which the slit opening is associated.

11. A container for radio tubes and the like including, an outer member, an inner member adapted to contain a tube telescoping within said outer member, said inner member including end wall sections and side wall sections connecting said end wall sections, one of said end wall sections having an opening through which the test end of the tube may be projected for test purposes, a flap associated with said outer member projecting inwardly into the container, a tab associated with said flap and a slit in one of said side wall sections cooperating with said tab to define and limit the telescoping movement of the test end of the tube.

12. A container for radio tubes and the like including, an outer tubular member having enclosing side wall panels, an inner member adapted to contain a tube telescoping within said outer member, said inner member including end wall sections and side wall sections connecting said end wall sections, a flap formed integrally with one of said side wall panels projecting inwardly into the container, a tab associated with said flap, and a slit of predetermined length cut in one of said side wall sections and operative to cooperate with said tab to define and limit the telescoping movement of the test end of the tube.

13. A container for radio tubes and the like including, an outer member comprising enclosing side walls, an inner member adapted to contain a tube telescoping within said outer member, said inner member including end wall sections and side wall sections connecting said end wall sections, one of said end wall sections having an opening through which the test end of the tube projects, a flap integrally formed with one of said side walls arranged to project inwardly into the container, and an enclosed slit of predetermined length cut in one of said side wall sections operative to engage the said flap to define and limit the telescoping movement of the test end of the tube.
